TION OF CONNECTICUT.

SYSTEM OF TRANSMITTING INTELLIGENCE.

1,351,775.

specification of Letters Patent. Patented Sept. 7, 1920.

Application filed August 3, 1917. Serial No. 184,235.

To all whom it may concern:

Be it known that I, GEORGE A. LONG, a citizen of the United States, residing at Hartford, in the county of Hartford and State of Connecticut, have invented certain new and useful Improvements in Systems of Transmitting Intelligence, of which the following is a specification.

This invention relates to a system of transmitting intelligence. Preferably the system comprises a plurality of stations, one or more constituting for instance subscribers' stations and another a central station. Each subscriber's station is furnished with equipment such as a telephone and through the agency of the subscribers the latter may talk or otherwise communicate with each other, through the intervention for instance of the central office operator or in some other manner. At each subscriber's station is another instrument by which the subscribers may also communicate with each other preferably though not necessarily, through the intervention of the central office operator. In the present instance these additional instruments are what are known as "telautographs." The various subscribers, therefore, may under proper control, communicate audibly with each other or with central, and in addition may transmit messages of a different type, which when telautographic or analogous instruments are utilized, are written. This system may be employed in different ways, for example for the transmission of telegrams which come into a telegraph office, having, of course, telephone equipment, by the way of a proper telautographic or equivalent instrument. I provide means whereby these conditions are made possible and wherein I also provide for the collection of the proper amount of toll. As a matter of fact there are other advantages attained by me which I will more explicitly hereinafter outline. I will also set forth in detail that form of embodiment of the invention which I have selected for illustration in the drawings accompanying and forming part of the present specification. This disclosure is primarily made to enable those skilled in the art to practice the invention. I am not restricted thereto, because I may depart therefrom in certain

particulars within the scope of the invention defined by the claims following said description.

In the drawings are four views identified respectively by Figure 1^a, Fig. 1^b, and Fig. 1^c and Fig. 1^d, showing a system involving the invention. The illustration for simplicity is divided but the figures collectively represent the system and indicate the nature of the invention.

As may be inferred there is a main line or main circuit. This may obviously be of any convenient character. That partly shown is denoted in a general way by 2. It is the present-day telephone line, although as will be clear the invention is not necessarily limited in this and other particulars. The power to the line 2 may be supplied in any of the usual fashions.

In addition to the main or primary circuit 2, there are several auxiliary or subordinate circuits as will hereinafter more particularly appear. The nature of the instruments at the stations (only three of which are shown) may also differ. I prefer, however, to employ a plurality of stations each equipped with a telephone, the subscribers of which can get into telephonic communication with each other through the central office. Beside this the stations, as distinguished from the central office, are equipped with instruments other than a telephone, and these instruments are generally and advantageously in the form of telautographs.

In Fig. 1^a I have shown a subscriber's station 3 furnished with equipment as will hereinafter appear. The subscriber is connectible with the central office or station 4. In Figs. 1^b and 1^c I have shown cord connections and their adjuncts. In Fig. 1^d I have shown another subscriber's station which in this case is supposed to be a telegraph office. I have not shown, however, any of the telegraphic sending instruments in the last mentioned view, as in the present case they do not necessarily concern the invention. I have, however, illustrated in said Fig. 1^a the telephone circuit and the telautograph circuit and the necessary co-operating instrumentalities.

Proceeding now with the description of Fig. 1^a and more especially the part to the

left thereof, the numeral 5 denotes a telephone and the numeral 6 a telautograph. The telephone instrument is well understood and the same statement applies with 5 respect to the telautograph which has been the subject of several U. S. patents. Therefore, it is not necessary for me to describe in detail either instrument, except in a general way, and sufficiently to point out the 10 action of the system.

The telephone equipment at the subscriber's station comprises a transmitter 7, a receiver 8 supported by its hook 9, the induction coil 10, condenser 11 and a ringer 12. 15 It will be clear that normally the telephone circuit is open. When the subscriber takes his receiver 8 from the hook 9 the latter is released and closed generally automatically, by spring means, to thus close the telephone 20 circuit and cut it into the line 2. This will result in lighting the lamp 13 at central office 4 and will indicate to the central office operator that a subscriber is on the line. It will be, of course, understood that the central office equipment is shown partly in Fig. 25 1^a and the remainder in Figs. 1^b and 1^c and partly in Fig. 1^d. As I have noted, when the subscriber at the station 3 takes his receiver 8 from the hook 9, the telephone circuit at the station 3 is closed and the lamp 13 at the central office station 4 will be lighted. When said lamp is lighted, this apprises the central office operator that the 30 subscriber desires something, and as a consequence she will insert her plug into the proper jack. The jack in question is that denoted by 14 on the right of Fig. 1^a, and as I observe when the lamp 13 is lighted as alluded to, she inserts the plug 15 (Fig. 1^b) 35 into the jack 14 and her head telephone 16 being on, she can get into telephonic communication with the subscriber, through the transmitter 17 at the station 3, when she operates the listening key 18 (Fig. 1^c). The 40 connection between the central office station 4 and the subscriber 3 is of course, made over the line 2.

In Fig. 1^d I have shown a station 19. This station is supposed to be a telegraph 50 office equipped of course, with the necessary instruments for the receipt and transmission of telegrams, which, however, I have not deemed it necessary to illustrate as they do not in themselves concern the invention. At 55 the station or telegraph office 19 there is a set 20 made up of the usual receiver 21 and transmitter 22.

It will be supposed that the subscriber at 60 station 3 desires to get into communication with the subscriber at the station 19, this having been determined previously by the insertion of the plug 15 in the jack 14. To put the two stations 3 and 19 into talking 65 connection the following procedure may be adopted: The central office operator will

first determine whether or not the station 19 is busy, in this case for example by touching the tip 20 of the plug 20' associated with the cord pair which she is using, to the sleeve of the jack of the line called for, 70 which I might note is a special multiple jack. It will be assumed that the line is open or is not busy. In this event she inserts the plug 20' in the jack 21' and thus puts the subscriber at the station 3 into talking 75 communication with the subscriber at the station 19, the latter subscriber being as I have already noted a telegraphic office, prior to which of course, the central office operator operates the ringing key 22' 80 (Fig. 1^c).

When the subscriber at the station 19 hears the bell 23 he knows that a subscriber desires to talk with him, and he, therefore, communicates with the subscriber at the 85 station 3 by operating the talking key 24 (Fig. 1^a) and determines the wishes of the party at station 3. It will be assumed that the party at station 3 desires to send a telegram. The mode of procedure to accomplish this result will be hereinafter set forth. I might say that I have but briefly described the telephonic connections between the two subscribers' stations and the central office. The invention does not necessarily concern 90 these. As a result they have been described quite concisely but yet sufficiently to comply with the statute. I have not deemed it necessary to even describe the additional jacks nor to refer to conditions which ensue 95 when the line is busy. I might observe that the jacks 25 and 26 which appear in Fig. 1^d are quite common in standard telephone equipment. It has not been thought necessary to allude to their functions because they 100 are so well understood.

The subscriber's station 3 as I have already explained is furnished with a telautograph which appears in Fig. 1^a. In Fig. 1^d at the second subscriber's station which in 110 this case is a telegraph office, is a similar telautograph 27. The telegraph office attendant upon ascertaining that the subscriber at station 3 desires to send a telegram says in effect "Hang up the receiver" 115 which in this case is the receiver 8 (left of Fig. 1^a) "Start the telautograph machine" as I will hereinafter point out, "And write your telegram. After you have finished writing your message stop the telautograph and take the receiver from the hook and wait until I can tell you what the charge is." 120 As the calling party at station 3 carries out these instructions the telegraph office attendant restores the talking key 24 to normal 125 and operates the key 27' (Fig. 1^a), which cuts the telautograph in onto the line 2 and cuts out all the telephonic apparatus at the telegraph office for the time being. By placing the receiver 8 back onto the hook 9 130

the relay 28 (Fig. 1^b) releases, opening the local circuit to one winding 30 of the double wound relay 31, (Fig. 1^b). This removes the shunt from around the answering supervisory lamp 32 which lights and shows that the receiver 8 has been hung up on the hook at station 3. As soon as the telegraph office attendant operates the telautograph key 27', the ground side of battery 33 (Fig. 1^a) is removed from one side of the line 2 and the ring strand of the cord circuit, so that the armature of relay 34 falls, opening the circuit to the other winding 35 of the double wound relay 31 which then becomes inoperative, and its armature which has been drawn up until this time releases, making contact with contact 36. Releasing of the armature of relay 31 makes a new circuit not heretofore established. The relay 37 (Fig. 1^c) being already energized, the ground side of battery 38 is connected at 39 and 40, thence to contacts 36 and 41 of relay 31, to contacts 42 and 43 of relay 44 (Fig. 1^b) which is not operated, to contacts 45 and 46 of relay 47 which is operated, to one side and through the winding of each of relays 48 (Fig. 1^b) and 49 (Fig. 1^c) to the negative side of battery 50. This closed circuit energizes relay 48 (Fig. 1^b) connecting contacts 51 and 52 and 53 and 54 respectively in relay 49 (Fig. 1^c) connecting contacts 55 and 56, and 57 and 58 respectively. As will be understood the two relays to which I have just referred are operated in synchronism. This operation cuts off practically all the apparatus associated with the operator's cord circuit (Figs 1^b and 1^c) and establishes a metallic connection from the subscriber's station 3 (Fig. 1^a) to the telegraph office (Fig. 1^d). The resistance 59 connected to the negative side of the battery 60, the positive side of which has a ground connection, keeps the answering supervisory lamp 32 extinguished by shunting it as soon as contacts 61 and 62 of relay 48 (Fig. 1^b) are made. A similar function is performed when relay 49 of Fig. 1^c is operated as the resistance 63 connected with the negative side of battery 64 shunts out the calling supervisory lamp 65 as soon as contacts 67 and 68 make connection. So long as relays 48 (Fig. 1^b) and 49 (Fig. 1^c) are operated, the supervisory lamps 32 and 65 will be dark, and if neither of the plugs is removed from the jacks, no interference or interruption will be experienced as the subscriber's operator cannot listen or ring on the circuit. It will thus be possible for the calling party at station 3 to then write a message on the telautograph 6 at the sending end, which will be transmitted to and reproduced on the telautograph 27 at the station 19 (Fig. 1^d). At this point the subscriber at station 3 after setting the telautograph 6 in action, operates the stylus 69 of said telautograph (assumed to be a sending

telautograph), the writing being reproduced by the stylus 70 of the receiving telautograph 27 in the telegraph office of station 19 (Fig. 1^d).

When the calling party completes writing the message the starting switch associated with the telautograph 6 will be operated to cut out said telautograph and the receiver 8 will be taken from the hook 9 by the party at station 3, ready for verbal verification of the message and information relative to the charges from the attendant at the telegraph office. The party at the receiving station 19 has in the meantime restored the telautograph key 27' (Fig. 1^d) to normal and operated the talking key 24. The party at the receiving end will then talk to the calling party at station 3 and ask that the amount of funds necessary to pay for the charges be deposited in the telephone 85 5 which in the present instance is the type of machine known as a "prepayment telephone."

A toll collector which meets my conditions in a satisfactory manner is such a one as is used with a telephone pay station. Some of these instruments collect the toll before the message is sent and some after. By this I mean after the verbal or before the verbal message is sent as distinguished from a telegram. As I already note a telephone pay station which is of the prepay type is the one I prefer naturally to use. An illustration of such a machine is set forth in Letters Patent No. 917,742 granted to me April 6, 1909 and to which reference may be had. This machine is diagrammatically illustrated in Fig. 1^a and is fully disclosed in said patent.

As I have stated after the telegraphic message has been sent in the present case from telautograph to telautograph, the next proceeding is the collection of the necessary toll. While the amount necessary to be deposited is named by the telegraph office the actual collection of the money is under the control of the telegraph operator. As I have thus far described the system and up to the present moment, the control of the system is for the time being under the control of the operator at the telegraph office. As will be understood a telephone pay station at the present time involves signals of distinct character which are sent over the line through the receiver in resonant connection with the signals to central office or telegraph operator. One signal indicates the deposit of a nickel, another a dime and another a quarter, these being the usual signals at present in vogue. They may be as will be inferred, transferred exactly in the manner set forth in the Letters Patent granted to me and already identified. Upon hearing the money signals and being satisfied that the proper amount of funds has 130

been deposited. the party at the receiving end telegraph office 19 will then dismiss the calling party at station 3 by saying that the charges have been paid for satisfactorily and the telegram will be sent at once. As soon as the calling party at station 3 hangs the receiver 8 on the hook 9, the party at the telegraph office or station 19 will press the coin collect key 71 (Fig. 1^a) sending 110 10 volt positive current through the resistance lamp 72, relay 73 onto the tip side of the line 2 to the tip spring 74 of jack 21' to the tip of the plug 20' and tip of the operator's cord circuit to the tip spring 75 of the jack 14 to the tip side of the line 2 through the subscriber's station 3 (Fig. 1^a) through the coin collector coils 76 through the contacts 77 and 78 to ground. This closed circuit not only deposits the money into the cash 20 box but also operates the relay 73 (Fig. 1^a) which lights the red pilot lamp 79 associated with the coin collecting circuit, and shows the telegraph office attendant that the coin collector has been operated and the money 25 has been collected.

The calling party at station 3 has already put the receiver 8 back onto the hook 9, while the attendant at the receiving end restores the keys 24 and 71 to normal and 30 operates the ring key 80 which sends out grounded generator current to the tip side of the line 2 and tip spring 74 of jack 21' and plug 20', and tip side of cord circuit (Figs. 1^b and 1^c) to contact 52 of relay 48 35 to condenser 81 through the winding of relay 82 to the ground. This operates relay 82 and connects contacts 83 and 84, putting ground onto one side of the winding 85 of the relay 44 through the winding of relay 44 to the negative side of the battery 86. This operates relay 44 which locks up until the answering plug 15 is removed from the answering jack 14 of the subscriber's line 40 (Fig. 1^a). Locking up relay 44 is caused by the ground on contact 87 (so long as relay 47 is operated) engaging with contact 88 of relay 44 which is connected to one side of the winding 85 with the negative side of the battery 86. The operation of relay 44 45 opens contacts 42 and 43 and removes the ground from the windings of relays 48 and 49 (Figs. 1^b and 1^c) which release and restore the cord circuit (Figs. 1^b and 1^c) to its normal telephonic condition; that is with the receiver 8 on the hook 9 at the calling station 3 the answering supervisory lamp 32 (Fig. 1^b) 50 will be lighted. As soon as the telegraph office attendant 19 (Fig. 1^a) restores all the keys to normal and relays 48 and 49 (Figs. 1^b and 1^c) release, the calling supervisory lamp 65 should light, signaling the central office operator that the connection may be 55 taken down.

What I claim is:

65 1. A system of the class described compris-

ing a station having a telephone and an instrument for the transmission of written intelligence, a second station also having a telephone and having an instrument for the receipt of such written intelligence, a central station having a telephone switchboard provided with means to connect the two telephones, and means to be set in action by the subscriber at the first station for cutting the telephone thereat off the line and for simultaneously cutting the instrument thereat into the line. 70

2. A system of the class described comprising a station having a telephone and a telautograph, a second station also having a telephone and a telautograph, the two telautographs being adapted to coöperate with each other, a central station having a telephone switchboard provided with means to connect the two telephones, and means to be set in action by the individual at one of the two first stations, for cutting the telephone thereat off the line and for simultaneously cutting the telautograph thereat into the line. 80 85

3. A system of the class described comprising a telephone and a telautograph, a second station also having a telephone and a telautograph, the two telautographs being adapted to coöperate with each other, a central station having a telephone switchboard provided with means to connect the two telephones, means for putting the telautographs into working relation with each other, and means operative from one of the two first 90 stations to prevent interference by the operator at the central office, during the transmission of a written message by the telautographs. 95

4. A system of the class described comprising a station having a telephone and a telautograph, a second station also having a telephone and a telautograph, the two telephones being adapted to coöperate with each other, a central station having a telephone 100 switchboard provided with means for the connection of the two telephones, and means to be set in action by the subscriber at the first station for cutting the telephone thereat off the line and for simultaneously cutting 110 the telautograph thereof into the line. 115

5. A system of the class described comprising a line, a plurality of stations, each station having instruments of two different characters one of which has means for transmission by writing of intelligence for reproduction by the complementary instrument, and means under the control of the individual at one of the stations, for automatically connecting the writing instrument to 120 the line through the action of one of said writing instruments. 125

6. A system of the class described comprising a line, a plurality of subscribers' stations each having instruments of two different 130

characters one being a telephone and the other a telautograph, the telautographs being adapted to coöperate with each other, a central station provided with means for the connection of the two telephones, and means under the control of the subscriber at one of the subscribers' stations, for connecting the telautograph at his station, with said line through the action of one of said telautographs.

7. A system of the class described comprising a line, a plurality of stations, each station having instruments of different characters, one of said instruments having means for the transmission of writing by intelligence for reproduction by the complementary instrument, and means for the collection of toll at one of the stations and for indicating the payment of the toll at the other of said stations.

8. A system of the class described comprising a line, a station having a pay telephone and a telautograph, a central station provided with a telephone switch board, an additional station having a telephone and a telautograph, means at the central station for putting the two telautographs into electrical correlation with each other, and means at the additional station for the collection of toll at the pay telephone.

9. A system of the class described comprising a line, a telephone station having a pay station and a telautograph, a central station having a telephone switch board, an additional station having a telephone and a telautograph, means governed solely by the operator at the central station for putting the two telautographs into correlation with each other, and means governed solely by the operator at the additional station for the collection of toll at said pay station.

10. A system of the class described comprising a line, a station having a telephone and a telautograph, a central station having a telephone switch board, an additional station having a telephone and a telautograph, means at the central station for putting the two telautographs into correlation with each other by way of said line, and means at the

additional station for the collection of toll at 50 the first mentioned station.

11. A system of the class described comprising a station having a telephone and a telautograph, a central station, an additional station having a telephone and a telautograph, means at the central station for putting the two telautographs into correlation with each other, and means at the additional station for the collection of toll at the first mentioned station.

12. A system of the class described comprising a station having a telautograph, a second station also having a telautograph, a central station, means under the control of the operator at the central station for putting the two telautographs into correlation with each other, and means controlled at the second station for the collection of toll at the first station for the transmission of a telegraphic message.

13. A system of the class described comprising a station having a telephone and also having an instrument for the transmission of intelligence, a second station also having a telephone, and an instrument for the receipt of such intelligence, a central station having a telephone switch board connectible by the operator thereat with the two telephones, and means at the second station for the collection of toll for the transmission of 80 the message containing such intelligence.

14. A system of the class described comprising a line, a plurality of subscriber's stations each having a telephone and a telautograph, the telautographs being adapted 85 to coöperate with each other, a central station provided with means for the connection of only the telephones, and means at one of the subscriber's stations, for connecting the telautograph at his station to the line and 90 independently of his telephone.

In testimony whereof I affix my signature in the presence of two witnesses.

GEORGE A. LONG.

Witnesses:

L. L. MARKEL,
HEATH SUTHERLAND.
